(57) **CLAIM**

An ornamental design for a pet grooming tool, as shown and described.

DESCRIPTION

FIG. 1 is a perspective view showing our new design; FIG. 2 is a top plan view;

FIG. 3 is a bottom plan view;

FIG. 4 is a first side elevational view;

FIG. 5 is a second side elevational view;

FIG. 6 is a front elevational view; and,

FIG. 7 is a rear elevational view.

Any broken lines denote probable environmental structure and are not part of the claimed design.
